UNITED STATES PATENT OFFICE.

SAMUEL M. GUSS, OF READING, PENNSYLVANIA, ASSIGNOR OF ONE-HALF
TO JACOB S. AMMON, OF SAME PLACE.

SHEAR-BLADE FOR HOT BLOOMS, BARS, &c.

SPECIFICATION forming part of Letters Patent No. 325,673, dated September 8, 1885.

Application filed June 20, 1885. (No model.)

To all whom it may concern:

Be it known that I, SAMUEL M. GUSS, a citizen of the United States, residing at the city of Reading, county of Berks, State of Pennsylvania, have invented a new and useful Improvement in Shear-Blades for Hot Blooms, Bars, &c., of which the following is a specification.

This invention is related more particularly to shears used in rolling-mills.

The object of the improvement is to adapt the blades of the shear, both fixed and movable ones, to shear bars, blooms, or plates while in a hot or heated condition without injurious softening of the blades, the practical use of the improvement having demonstrated that the cutting life of the shear-blades constructed in accordance with my invention is equal to from four to six times the life of an ordinary shear-blade employed upon the same class of bars, plates, and blooms immediately after they have left the rolls.

The accompanying drawings will show clearly to an expert the nature of my invention, like letters of reference indicating like parts.

Figure 1 represents a portion of a shear with my improvement attached to the same; Fig. 2, a front elevation, partly in section, of the ordinary shear-blade adapted to use my improvement; Fig. 3, a detached shear-blade as cast of steel or cast-iron (chilled) with my improvement partly in section; Fig. 4, a section through the blade on the line *a a* of Fig. 2.

Since the introduction of steel-mills it has become quite general to cut the ingots, blooms, bars, &c., while hot, thereby saving one handling of the product, and iron-mills have also undertaken to do the same. Although a saving is effected thereby, it is also a source of annoyance, from the fact that frequently the blades of the shears will give out before the hands have run out their turn, necessitating a change of shear-blades, which means accumulation of stock, idleness of a portion of the hands, increased strain upon the shear, and waste of power in the subsequent cutting up of the stock in a cold state. My improvement makes it feasible to run the shear continuously during the turns, changes of blades

being (except in case of breakage) made between the turns.

I have shown the improved blades attached to an alligator-shear, and an expert will readily see that it is equally applicable, and, in fact, more readily applied, to the modern mill-shear.

A represents the bed; A', the fulcrum; B, the movable jaw; C C, the blades.

D is a chamber drilled in the ordinary shear-blade near the cutting-edge when remodeling the same to adapt them to my improvement, and which I make usually three-quarters of an inch or more in diameter.

E represents a thread, and F a thimble screwed therein.

G is the supply-pipe, usually about three-sixteenths of an inch in diameter. This pipe passes through the T-piece H, being threaded and screwed in the outer end of the same, and is projected beyond the face to receive a union, I, by which a removable connection is made with the supply-pipe J. The thimble F provides an annular passage around the pipe G, the latter being projected within the chamber D to about one-fourth of an inch of the rear of the same. The T-piece H forms an extension of the circulating-chamber, the discharge from which is regulated by the cock K. Changes of blades are made by breaking the connection at the union I.

I prefer to construct the blades as shown in Fig. 3, with the chamber H' integral with the blade and chamber D, by which construction less machine-labor is required in their preparation and loose pieces are dispensed with.

The blades may be made of cast-iron with the cutting-faces cast upon chills, and will wear a long time and make a satisfactory cut; but I prefer to cast them directly of steel and temper them for the purpose desired.

In operation the pipe J is connected with a reservoir of water, of sufficient height above the shear to insure the passage of water through the tube G into the chamber D, with which it passes, and leaves the same by the annular space around the pipe G. The speed of the current passing through the chamber is regulated by the cock K, and the escaping water may be discharged upon and in a line

with the cutting-edge of the blade. A flexible hose, J', or its equivalent may be used for the supply of the movable blade.

It will be found in a practical use of my improvement that the blades are not heated enough to draw their temper, although constantly employed cutting red-hot blooms, bars, &c., and require less power to operate, owing to their retention of a cutting-edge from the circulation of the water within the same.

Having described the construction, use, and operation of my improved shear-blades and recited their advantages over the ordinary blades, I desire to secure by Letters Patent the following claims thereon:

1. As an improvement in the construction of shears for shearing heated metal bars, &c., a hollow or chambered cutting-blade, jointly

with a tube for conveying water to and through the same, and having an orifice closed by a cock for discharging and regulating the flow of water therefrom, substantially as shown, described, and for the purpose set forth.

2. The combination, with a hollow or chambered shear-blade having a circulating-pipe forming a part of the same, as described, of a reservoir or pressure-head of water by pipe J and union I, the supply of water to and the circulation of the same within said chambered blade being controlled by the cock K, substantially as and for the purpose set forth.

SAML. M. GUSS.
